UNITED STATES PATENT OFFICE.

MARTIN SANDERS, OF CHICAGO, ILLINOIS.

SPARK PLUG.

Application filed August 26, 1926. Serial No. 131,612.

My invention relates to an improvement in spark plugs, the invention being more particularly related to an improved electrode construction especially designed for 5 use as a repair attachment for spark plugs, although it is to be understood that my invention is not confined to such use since the improved electrode construction can be made 10 as a component part of the spark plug in the first instance.

It is within the province of my invention to provide an electrode construction capable of being quickly and conveniently applied to the central electrode of a customary type 15 of spark plug embodying a conducting shell insulatively carrying a central electrode; and further to provide the electrode construction with an extending part which will occupy a position continuous in proximity 20 with the periphery of the conducting shell so that sparks will be produced in a continuous intervening spark gap to insure a more complete burning of the gas mixture 25 in the cylinder.

Other objects will appear hereinafter.

The invention consists in the combinations and arrangements of parts hereinafter described and claimed.

The invention will be best understood by 30 reference to the accompanying drawing, forming a part of this specification, and in which,

Fig. 1 represents a side elevational view of a spark plug equipped with my improved 35 electrode construction;

Fig. 2 represents a central longitudinal section of Fig. 1;

Fig. 3 represents a bottom plan view of 40 Fig. 1, this view being taken on the line 3—3 of Fig. 2; and

Fig. 4 represents an enlarged perspective view of my electrode construction.

With more particular reference to the accompanying drawing, wherein for the purpose of illustrating a practical application 45 of my invention, I have shown a spark plug 5 of ordinary construction, the same including an outer conducting shell 6 and a central electrode 7 which is insulatively supported therein through the instrumentality 50 of a porcelain center piece 8 and a locking sleeve 9.

My invention, in its preferred form of 55 construction as illustrated in the accompanying drawing, comprises an attachment which is adapted to be applied to the free end of

the electrode 7 and which for this purpose is made with a medial sleeve 10 slit longitudinally as at 11 in order to have a tight binding grip on the central electrode 7 when 60 applied thereon. From what I term the outer end or portion 12 of this sleeve, an extending portion 13 extends outwardly from an edge of the stock where the slit 11 occurs, and supports a circular or encircling part 65 14 which stands apart from the end of the sleeve, the extremity 15 of the circular or encircling part 14 preferably terminating, as best shown in Figs. 3 and 4, in spaced apart relation to the outwardly extending 70 part 13 where it merges into the encircling part 14. Preferably and as shown, the encircling part 14 is held spaced from the sleeve 10 at such distance that it will occupy a position opposite the end 16 of the conducting shell 6 when the sleeve 10 is applied to the central electrode 7, as best shown in 75 Figs. 1, 2 and 3. By this arrangement, the encircling part 14 is supported continuously in proximity to the end 16 of the conducting 80 shell so as to produce a continuous spark gap therewith, and the result of this arrangement is that a field of electrical discharges or sparks will take place between the inner edge 17 of the encircling part 14 and 85 the end 16 of the conducting shell whenever through the employment of the usual timing device the electrical current is permitted to flow through the central electrode 7.

It is to be remarked here, in order that 90 the mode of applying my attachment may be better understood, that in addition to the central electrode 7, the ordinary spark plug has a second electrode (not shown) of angular form which has one end fixed in the 95 end 16 of the conducting shell and which has its opposite end terminating in close proximity to the free end of the central electrode 7. Inasmuch as this angular electrode as 100 usually arranged, interferes with the application of my improved electrode construction to the end of the central electrode 7, it is necessary to remove that portion of the angular electrode which protrudes from the end 16 of the conducting shell; and in Fig. 2 105 of the accompanying drawing I have shown at 18 the embedded part or stub of an angular electrode sheared off even with the end 16 so as to enable the application of the sleeve 10 to the central electrode 7.

From the foregoing description and a 110 study of the drawing it will be apparent

that I have provided a very simple and inexpensive electrode construction, capable of being manufactured as a repair attachment which can be quickly and conveniently fixed on the central electrode when the spark plug fails to function properly owing to any impairment of its electrodes, and which when applied will serve as means for insuring a more effective burning of the gas mixture in the cylinder. It will be obvious that, if desired, the electrode construction of this invention may be made as a component part of the central electrode in the first instance.

While I have illustrated and described the preferred form of construction for carrying my invention into effect, this is capable of variation and modification without departing from the spirit of the invention. I,

therefore, do not wish to be limited to the precise details of construction set forth, but desire to avail myself of such variations and modifications as come within the scope of the appended claim.

Having described my invention, what I claim as new and desire to secure by Letters Patent is:

An attachment for spark plugs comprising a flat band of conductive material bent to form a central spring sleeve portion to engage the central electrode and then curved outwardly from said sleeve terminating in a substantially cylindrical outer portion, substantially as described.

In testimony whereof I have signed my name to this specification.

MARTIN SANDERS.
